The ornamental design for a bottle wrap, as shown and described.

DESCRIPTION

FIG. 1 is a top-front perspective view of a bottle wrap showing our new design.

FIG. 2 is bottom-rear perspective view thereof.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof; and,

FIG. 8 is a bottom plan view thereof.

The evenly broken lines that appear throughout the figure set depict perforation lines in the bottle wrap. The dot-dash lines that appear in the figures represent environmental details that form no part of the claimed design.
